UNITED STATES PATENT OFFICE

GEORG EGLY, OF BERLIN, GERMANY, ASSIGNOR TO GEBRÜDER SIEMENS & CO., OF BERLIN-LICHTENBERG, GERMANY, A CORPORATION OF GERMANY

MANUFACTURE OF RESISTOR RODS WITH THICKENED PORTIONS

Application filed December 31, 1926, Serial No. 158,392, and in Germany April 10, 1926.

My invention relates to the manufacture of resistor rods with thickened portions.

It is well known to thicken or enlarge resistor rods in certain places, particularly at the terminals at which they are connected in circuit, in order to reduce the resistance and consequently heat developed at those places. It was hitherto customary to bring about the desired thickening or increase in diameter of the rods by pushing short pieces of tube, collars or bushings over them and fixing these members in place by means of a suitable bonding material. This method of producing the thickened places or enlargements is, however, unreliable and difficult. It has in particular been found in practice that the contact resistance between the central core rod and the collar or bushing is very variable.

My invention consists in laterally applying to the resistor rod at the current terminals at which it is to be thickened, enlarged or increased in diameter, bodies consisting of conducting material the attachment surfaces of which have substantially the same shape or configuration as the surface of the resistor rod and interposing a layer of a suitable paste or bonding material between them. It is then unnecessary to slip as heretofore the enlarging bodies of conducting material over the core rod, and they are simply applied to the sides of the rod. This may be effected by coating the individual conducting bodies or the core rod or both of them with the paste or the like and by pressing the parts together. In this way the paste or bonding material is uniformly distributed between the parts to be combined and the pressure applied ensures a particularly intimate connection between them. The conductivity of the thickened portion of the rod obtained in this manner is very uniform and permits of a reliable manufacture on a large scale, scrap being almost entirely avoided. According to my invention parts of a longitudinally split tube of a similar material as, or preferably of a better conducting material than the core rod is chosen as a suitable body of conducting material. In many cases the halves obtained by splitting a tube longitudinally are most conveniently employed for the purpose. For bind-

ing the applied conducting body with a rod a plastic material or paste is employed as bonding material which is similar in its qualities to that of which the conducting body is constructed or consists of the same material. These enlarged terminals of the resistor rod may be consolidated and finished by again baking or burning the rod with the applied bodies. 55

In the drawing affixed hereto an embodiment of my invention is illustrated by way of example.

In the drawing

Fig. 1 shows an end-elevation of a resistor rod thickened in one place according to my invention, and

Fig. 2, a side-elevation of the same.

Like parts are indicated by like letters of reference in both figures of the drawing.

Referring to the drawing A is the resistor rod to which are applied the two halves B and C of a tube obtained by splitting a short sleeve lengthwise. Prior to the application of the parts B and C the rod A has been coated with a bonding substance D at the place at which it is desired to thicken the diameter of the rod. The rod with the applied pieces is then again subjected to a baking process or other heat treatment and thus consolidated and finished. 80

Such enlarged terminals may, as a matter of course, be produced at the ends of the rods as well as in other places. They may, for instance, be produced at a certain distance from the ends of the rod and the conductivity of the ends may be increased by a metal coating which coating may extend to the terminal of the rod. In this way forms of rods are obtained which are suitable for many purposes. In particular it is possible in this way to produce comparatively light rods which are suitable for use at very high temperatures and possess at the same time a good metallic contact at their ends. The metal coating is effectively protected against 90 the effect of the high rod temperatures by the thickened or enlarged portion located in front of it. 85

Various modifications and changes may be made without departing from the spirit 100

and the scope of the invention, and I desire, therefore, that only such limitations shall be placed thereon as are imposed by the prior art.

I claim as my invention:

- 5 Method of producing thickened terminal portions on a resistor rod, consisting in applying a thin coating of pasty resistor material to said rod portions, pressing complementary terminal elements of conducting
- 10 material and of similar configuration as the rod portions laterally against the coated portions and then firing said rod portions to produce a firm conductive bond between the rod portions and the terminal elements.
- 15 In testimony whereof I affix my signature.

GEORG EGLY.
